UNITED STATES PATENT OFFICE.

CHARLES BRENT, OF BUFFALO, NEW YORK.

VACUUM-PUMP.

1,145,181.

Specification of Letters Patent.

Patented July 6, 1915.

Application filed November 10, 1911. Serial No. 659,497.

To all whom it may concern:

Be it known that I, CHARLES BRENT, a subject of the King of England, residing at Buffalo, in the county of Erie and State of 5 New York, have invented certain new and useful Improvements in Vacuum-Pumps, of which the following is a specification.

This invention relates to improvements in vacuum pumps utilized in vacuum cleaners.

10 More specifically the invention relates to a pump comprising a casing provided with a suitable down-pipe structure having a water nozzle mounted at the upper end and adapted to engage the blades of a rotor rotatably mounted in a casing secured and preferably in communication with the down-pipe structure. It is preferable to give these blades a little turn toward the stream to facilitate the action of the water against the 15 same.

The invention may be further briefly summarized as consisting in the construction and combination of parts hereinafter set forth in the following description, drawings 20 and claims.

Referring to the drawings, Figure 1 is a vertical section through the casing showing the rotor in elevation; Fig. 2 is a vertical section taken at another angle showing the 25 blades in elevation.

In carrying out the invention any preferred form and construction of parts may be employed so long as they possess the necessary characteristics, but I have shown one 30 form in the drawings which is highly effective in operation, and in such embodiment 1 represents a suitable down-pipe member having threaded in the upper end thereof a nozzle 2 provided with an opening 3 adapted to project its stream down the pipe. The lower end of the pipe is externally threaded for receiving a down pipe extension 4. The side of this down pipe member 1 is provided with a flat surface 5 35 having a vertically disposed opening 6 which communicates with a rotor casing 7 secured to the flat surface 5 by means of screws 8 passing through a flange 9 forming a part of the casing 7. The casing 7 is further 40 provided on one side with a boss 10 to receive a screw 11 forming the shaft for supporting a rotor hub 12 which is provided with suitable blades 13, the ends 14 of which curve upward toward the nozzle as shown. 45 The opposite side of the casing 7 is provided 50

with a threaded nipple 15 receiving a suitable air connection not shown.

In operation the water passes through the opening 3 in the nozzle 2, spreads slightly and impinges against the blades 13, causing 60 the rotor to revolve at great speed with the result that air is drawn in through the pipe 15 by the rotor and by the suction created by the downward flow of the water through the 65 down pipe construction.

It has been found in use of the foregoing device that a very effective degree of vacuum is produced with a large volume of air handled by reason of the fact that when the air inlet is closed, as in operation, a small volume of water collects in the casing 7 where it is churned up so to speak with the air forming a foam which passes down through the pipe 4. The pipe 4 should be of a sufficient length to produce a reasonably high 70 vacuum, the down pipe being the vacuum producing feature while the rotor accounts for the large volume of air handled. 75

Having described my invention, I claim:—

1. In a vacuum pump, a casing forming 80 a single air admission and air and water mixing chamber, an inlet member communicating with said casing, a liquid nozzle mounted to project a stream of liquid into said casing, an air and water discharge 85 pipe leading from said casing, and a single rotor mounted in said casing in a position to be driven by a stream of liquid from the nozzle and to draw air in through the inlet.

2. In a vacuum pump, a casing forming 90 a single air admission and air and water mixing chamber, an inlet member communicating with said casing, a liquid nozzle mounted to project a stream of liquid into said casing, an air and water discharge 95 pipe in alignment with the nozzle and leading from said casing, and a single rotor mounted in said casing in a position to be driven by a stream of liquid from the nozzle and to draw air in through the inlet. 100

3. A vacuum pump comprising a casing forming a single chamber for the admission and mixture of liquid and air, a down pipe structure secured to said casing and in open communication therewith, a liquid nozzle mounted in the upper end of said down pipe structure, a discharge pipe mounted at the opposite end, an inlet member communicating with substantially the center of said casing, and a single rotor mounted within 105 110

2
said casing and consisting of a supporting portion and blades extending into the down pipe structure, whereby the blades of the rotor are engaged by the stream of liquid, 5 and air is drawn into the casing through the inlet opening and mixed with water in the casing.

4. In a vacuum pump, a casing, an inlet member entering the same, a rotor mounted 10 within said casing and having its center substantially in alinement with the air inlet member, a down pipe structure secured to and communicating with said casing, a nozzle

mounted in the upper end of said down pipe structure and having its discharge 15 opening in alinement with the same, and a discharge pipe secured to the lower end of said down pipe structure.

In testimony whereof I affix my signature in the presence of two witnesses as 20 follows.

CHARLES BRENT.
